ATTORNEY.

UNITED STATES PATENT OFFICE.

LOUIS PICHLER, OF CLEVELAND, OHIO.

WINDSTORM HAT CATCH.

Application filed September 30, 1920. Serial No. 413,684.

To all whom it may concern:

Be it known that I, LOUIS PICHLER, a citizen of the United States, residing at Cleveland, in the county of Cuyahoga and State 5 of Ohio, have invented certain new and useful Improvements in Windstorm Hat Catches, of which the following is a specification.

This invention relates to hat retainers and 10 is especially adapted to retain the hat even though the latter should be blown from the head of the wearer.

An object of the invention is to provide a retainer which is engageable with the person 15 of the wearer and is adjustable to conform to different requirements in sizes of persons using same as well as difference in sizes of hats, etc.

The above and other objects of this invention will be in part described and in part 20 understood from the following description of the present preferred embodiment of the invention taken in connection with the accompanying drawings, wherein:

25 Fig. 1, is a perspective view of a retainer constructed in accordance with this invention.

Fig. 2, is a vertical sectional view taken 30 through the casing, and

Fig. 3, is a sectional view taken on the line 3—3 of Fig. 2, and looking in the direction of the arrow.

The device of this invention consists of a drum 4 stamped from a sheet of metal and 35 having portions of its periphery bent laterally in alternate directions to provide lugs 5, each of which is turned upwardly at right angles. It will be observed that by forming the drum in this way a grooved outer periphery is provided as shown to advantage 40 in Fig. 2 of the drawings.

Extending centrally through the drum is a shaft 6, the opposite ends of which are reduced to provide pintles which are mounted 45 in the opposite sides of a casing 7. Constructing the shaft in this manner the device will stand more wear, and assure efficient operation of the mechanism and can not misplace the shaft from its required position 50 and make the device useless. The casing in

the present instance is shown to be of a rectangular configuration, although it is to be understood that this may be of any desired shape and made of any desired material. A suitable securing means is secured to the back of the casing by which the latter is held to the person of the wearer. In the present instance I have shown a pin 8, which is held on the casing by lugs 9 which are struck out from the latter.

Convoluted on the shaft 6 and having one end secured thereto is a flat spring 10 which has its opposite end secured to the drum 4. Since the drum is revolvably mounted upon the shaft it will be apparent that the expansive force of the spring will normally cause the drum to be retained in a tensioned position for the purpose of holding a cable or chain 11 thereon in a wound-up position. This is permitted by reason of the fact that one end of said chain is secured to the drum while the opposite end is preferably equipped with a clasp 12 which embraces the hat. In order that the drum might be held in any desired adjusted position, a pawl 13 is provided, one end of which is pivoted upon the drum, and the opposite end enlarged to provide a weight, said weight as shown has the advantage of proper swinging movements, and assuring the tooth, 14, to engage in the recesses with force and quick action and keep the pawl from slipping. A tooth is formed on one margin of the pawl as indicated at 14 and is adapted for engagement in recesses 15 which are formed in the shaft 6.

In use the casing is secured to the person of the wearer in an obvious manner. The chain 11 is then withdrawn from the drum through a suitable opening in said casing until the desired length of chain is produced, pursuant to which the clasp is engaged with the hat. The cable 11 is adjusted by merely exerting pressure thereon in an obvious manner.

What is claimed is:

A wind storm hat catch including a casing equipped with a drum, said drum comprising a disc the periphery of which has portions thereof bent laterally in opposite directions, a spring mounted on one side of

the disc within the plane of the portions projecting on one side, and a pawl pivotally mounted on the opposite side of the disc within the plane of the portions projecting on the opposite side, a cable having its outer end adapted for engagement with the hat, and a shaft extending through said disc and fixedly engaged with said casing, said shaft

being adapted for engagement by the pawl substantially as described.

In testimony whereof I affix my signature in presence of two witnesses.

LOUIS PICHLER.
